AXIALLY SLIDABLE SUPPORTING MEANS
FOR GRINDING WHEELS

Carl Gustav Ekhholm, Lidköping, Sweden, assignor
to Lidköpings Mekaniska Verkstads Aktiebolag,
Fabriksgratan, Lidköping, Sweden, a corpora-
tion of Sweden

Application October 11, 1939, Serial No. 298,877
In Germany October 31, 1938

5 Claims. (Cl. 51—48)

In some grinding operations good results have been achieved by using a grinding wheel, which during the grinding operation is simultaneously rotated and displaced along the workpiece parallel with the grinding wheel axis. In the known grinding machines of this kind the grinding wheel was firmly mounted on a spindle, which was both rotatably and slidably mounted. This arrangement, however, has the disadvantage that the axial displacement requires considerable power and results in wear on expensive machine elements. Furthermore there are difficulties in mounting the spindle in antifriction bearings.

The present invention relates to an improved axially displaceable supporting means for grinding wheels by means of which disadvantages stated above are obviated. The supporting means according to the invention is characterized thereby that a hub supporting the grinding wheel is slidably mounted on a rotatably mounted spindle by means of balls or rollers, preferably balls, said hub being connected with the spindle in the direction of rotation. According to the invention the grinding wheel is easily slidable with very small power consumption.

An embodiment of the invention is shown in the accompanying drawings. Fig. 1 shows a longitudinal section through the improved supporting means. Fig. 2 shows a horizontal view of a grinding wheel of a centerless grinding machine mounted according to the invention.

The grinding wheel 1 shown in Fig. 1 is supported by a sleeve 2 between a flange 3 and a nut 4. The sleeve 2 in its turn is supported by a hub 5 between a flange 6 of the hub 5 and a nut 7. The unit consisting of the grinding wheel, the sleeve and the hub is slidably mounted on the grinding wheel spindle 8 which on both sides of the grinding wheel is mounted in fixed axial position by means of double row self-aligning ball bearings 10, 11. On both sides of the ball bearings there are sealing members 12, 13, 14, 15. The left end of the spindle in Fig. 1 is connected to a motor (not shown) for rotation of the spindle.

In order to facilitate the sliding of the hub 5 on the spindle 8 slidable ball bearings are arranged between these two parts at both ends of the hub 5. Each such ball bearing consists of a hardened steel bushing 16 and 17 pressed into the hub and a hardened steel bushing 18 and 19 pressed onto the spindle 8 and ball retainers 20 and 21 freely placed between said bushings and containing a great number of balls distributed in the longitudinal direction of the ball retainer as

well as in its peripheral direction. In the shown embodiment each ball retainer consists of a cylindrical tube having bores for the balls. The balls are retained by lips bent out of the material of the tube. Between the inner hardened steel bushings there is placed an intermediate piece 22 of some softer material.

In Fig. 1 the hub 5 is shown in its left end position, there being an interspace between the right end surface of the hub 5 and the adjacent surface of the sealing member 14. To prevent intrusion of grinding dust or other foreign material through this interspace into the slide ball bearings the sealing members 13, 14 are provided with projecting sealing ribs 23, 24, which cooperate with corresponding sealing grooves in the end surfaces of the hub 5.

To promote the axial displacement of the grinding wheel a rod 25 is slidably mounted in a longitudinal bore in the spindle 8 and connected with the hub 5 by means of a key 26. The key 26 extends through slots 27 cut out in the spindle 8 and the tube 22. The slots have such a length that they permit the necessary movements of the key 26. The rod 25 extends outside the end of the spindle and is connected with a block 29 by means of double-acting thrust ball bearings 28. The block 29 is slidably but not rotatably mounted in a housing 30 arranged on the outside of the machine bed 9. The block 29 is formed with an externally threaded shaft 31 extending through a bore in the housing 30. An internally threaded sleeve 32 encloses the shaft 31 and is in thread-engagement with said shaft. The sleeve 32 is mounted in an enlargement of the bore in the housing 30. A hand-wheel 34 is firmly mounted on the end of the sleeve 32 by means of a nut 35.

By turning the hand-wheel 34 in the one or the other direction the sleeve 32 is turned. Said sleeve has a fixed axial relation to the housing 30. On account of the thread-engagement between the sleeve 32 and the shaft 31 this turning results in an axial displacement of the shaft 31 in the one or the other direction. This axial displacement is transmitted through the block 29 and the thrust bearing 28 to the rod 25 and through the key 26 further to the unit consisting of the hub 5, the sleeve 2 and the grinding wheel 1.

In the shown embodiment the key 26 also has the function to transmit the rotation of the spindle 8 to the hub 5 and the grinding wheel 1. Also the rod 25 is rotated, but on account of the double acting thrust bearing 28 the movements of the

non-rotating block 29 can be transmitted to the rod 25 even when the spindle is rotating.

Fig. 2 shows the supporting means according to the invention used in a centerless grinding machine having a grinding wheel 1 and a regulating wheel 36 and a work support not shown in the drawings. The grinding wheel is shown in its left end position, the right end position being indicated in dot and dash lines. The workpiece to be ground is a torsion spring having a cylindrical intermediate portion 37 and two fluted end portions 38 and 39. The intermediate portion is connected with the end portions by transitions forming surfaces of rotation 40, 41 with curved generatrices.

The grinding operation relates to the cylindrical surface of the intermediate portion and to the surfaces 40, 41 of the transitions. The surface-quality of the transitions is of great importance as to the strength of the finished torsion spring, as even small fissures in the transitions act as indications for breakage. It is therefore desirable that the transitions should be ground so as to eliminate all fissures that might have occurred during the foregoing operations in an economical manner.

The end portions of the grinding wheel are used for the grinding of the transitions. For this purpose the end portions of the grinding wheel before the grinding operation are shaped as surfaces of rotation having curved generatrices, the shape of which corresponds with the desired shape of the torsion spring. During the grinding of the cylindrical surface of the torsion spring the grinding wheel is axially displaced by turning the hand wheel 34. One of the end portions of the grinding wheel comes in contact with one of the transitions of the torsion spring, and the grinding at the transition is continued until the operator finds the surface satisfactory. For a satisfactory result of the grinding operation it is necessary that the axial displacement of the grinding wheel during the grinding of the transitions takes place uniformly. In the supporting means according to the invention this is possible, because only a relatively small mass is to be displaced and the slide bearings between the slide unit and the spindle cause only very little friction.

The invention is not restricted to the embodiment shown in the drawings but numerous modifications of the same are possible. The slide bearings may for instance consist of an inner bushing fixed on to the spindle and having axially extending outwardly projecting ribs and an outer bushing connected with the grinding wheel and having inwardly projecting ribs, situated between the first mentioned ribs and rows of balls or rollers placed between the different ribs. Such slide bearings can also transmit the rotation of the spindle to the grinding wheel. For this purpose as a further alternative the spindle and the bore of the hub could be made polygonal preferably square in cross section, and a number of balls or rollers be placed between the hub and the spindle to reduce the friction when sliding the grinding wheel. When the key is relieved

from the function of transmitting rotation it can be arranged out of contact with the slideable rod and the hub, whereby all sliding friction in connection with the movement of the key is obviated. The invention is not restricted to centerless grinding machines but can also be used in connection with grinding machines having fixed centres. Furthermore the invention is not restricted to grinding machines but can also be used in lapping or polishing machines.

I claim:

1. In a supporting means for a grinding wheel the combination with a rotatably mounted spindle formed with a bore, of a grinding wheel hub and antifriction slide bearings between the hub 15 and the spindle, a rod slidably mounted in the bore in the spindle, and a connecting member such as a key between the rod and the hub.

2. In a supporting means for a grinding wheel the combination with a rotatably mounted spindle 20 formed with a bore, of a grinding wheel hub and antifriction slide bearings between the hub and the spindle, a rod slidably mounted in the bore in the spindle, a connecting member such as a key between the rod and the hub, a block mounted 25 slidably but not rotatably in a housing, a thrust bearing situated outside the end of the spindle and connecting the rod with a block.

3. In a supporting means for a grinding wheel the combination with a rotatably mounted spindle 30 of a grinding wheel hub and antifriction slide bearings between the hub and the spindle, a rod slidably mounted in a bore in the spindle, a connecting member such as a key between the rod and the hub, a thrust bearing situated outside 35 the end of the spindle and connecting the rod with a block mounted slidably but not rotatably in a housing and provided with a threaded shaft, an operating sleeve rotatably mounted in the housing and having internal threads in thread- 40 engagement with the threaded shaft.

4. In a supporting means for a grinding wheel the combination with a rotatably mounted spindle, of a grinding wheel hub, slideable on the spindle, ball retainers at both ends of the hub 45 containing a number of balls distributed axially as well as peripherally, two bushings pressed into the hub at the ends thereof and two bushings pressed on to the spindle for coaction with the balls, means for rotating the grinding wheel hub 50 with the spindle and means located between the two sets of balls for reciprocating the grinding wheel hub on the spindle.

5. In a supporting means for a grinding wheel 55 the combination with a rotatably mounted spindle, of a grinding wheel hub, ball retainers at both ends of the hub containing a number of balls distributed axially as well as peripherally, two bushings pressed into the hub at the ends 60 thereof and two bushings pressed on to the spindle for coaction with the balls, means for rotating the grinding wheel hub with the spindle, said means also forming means for reciprocating the grinding wheel hub on the spindle.

CARL GUSTAV EKHOLM.
